Primary Examiner — T Chase Nelson*Assistant Examiner* — Sydney Margaret Parsley(74) *Attorney, Agent, or Firm* — Geoffrey Lottenberg; Berger Singerman LLP(57) **CLAIM**

The ornamental design for a theater structure, as shown and described.

DESCRIPTION

FIG. 1 is a perspective view of a theater structure of the subject disclosure;

FIG. 2 is a front view thereof;

FIG. 3 is a rear view thereof;

FIG. 4 is a right view thereof;

FIG. 5 is a left view thereof;

FIG. 6 is a top view thereof, and,

FIG. 7 is a bottom view thereof.

The broken lines illustrate portions of the theater structure that form no part of the claimed design.
